UNITED STATES PATENT OFFICE

119,397

DESIGN FOR A SHOE OR SIMILAR ARTICLE

Andre Perugia, Paris, France

Application December 29, 1939, Serial No. 89,205

Term of patent 3½ years

To all whom it may concern:

Be it known that I, Andre Perugia, a subject of the Kingdom of Italy, residing in Paris, France, 2 rue de la Paix, have invented a new, original, and ornamental Design for a Shoe or Similar Article, of which the following is a specification, reference being had to the accompanying drawing, forming part thereof:

Figure 1 is a perspective view of a shoe or similar article, showing my new design.

I claim:

The ornamental design for a shoe or similar article, as shown.

ANDRE PERUGIA.
